[57] CLAIM

The ornamental design for an electric insect killer, as shown and described.

DESCRIPTION

FIG. 1 is a view in perspective of an electric insect killer embodying our ornamental design.

FIG. 2 is a view in front elevation thereof, the view in rear elevation being a mirror image thereof.

FIG. 3 is a view in right side elevation thereof, the left side elevation being a mirror image thereof.

FIG. 4 is a top plan view thereof.

FIG. 5 is a bottom plan view thereof.

FIG. 6 is a view in perspective of a second embodiment of electric killer embodying our decorative design.

FIG. 7 is a view in front elevation of the second embodiment, the view in rear elevation being a mirror image thereof.

FIG. 8 is a view in right side elevation of the second embodiment, the left side elevation being a mirror image thereof.

FIG. 9 is a top plan view of the second embodiment.

FIG. 10 is a bottom plan view of the second embodiment.

FIG. 1.

FIG. 2.

FIG. 4.

FIG. 5.

FIG. 3.

FIG. 6.

FIG. 7.

FIG. 9.

FIG. 8.

FIG. 10.
